UNITED STATES PATENT OFFICE.

IDA M. BOND, OF FOREST HILL, NEW JERSEY.

CORSET AND CORSET-WAIST.

No. 874,386.

Specification of Letters Patent. Patented Dec. 24, 1907.

Application filed May 9, 1907. Serial No. 372,790.

To all whom it may concern:

Be it known that I, IDA M. BOND, a citizen of the United States, residing at Forest Hill, Essex county, New Jersey, have invented 5 certain new and useful Improvements in Corsets and Corset-Waists, of which the following is a full, clear, and exact description.

My invention relates to improvements in women's wearing apparel, and particularly 10 to an improved corset or corset waist.

The object of the invention is to provide a simple and efficient abdominal supporter in combination with the corset or corset waist, the parts coöperating so that while the sup- 15 porter will give a suitable contour to the figure, the corset portion can be readily adapted to the final adjustment of the abdominal sup- porting member.

In the accompanying drawings Figure 1 20 is a perspective view of my invention as applied to the figure, with the front part of the corset thrown open; Fig. 2 is a similar view, the supporter being cast off and the figure of the wearer being omitted.

25 1—1 represent the two back members of the corset with the usual lacings 2. Connected to the back member are the front members 3—3, which may be provided with the usual clasp fastenings, although other 30 fastenings may be substituted. At each side and between the front and back are slitted portions extending upwardly a suitable distance from the lower edge of the garment, and provided with adjusting lacings 35 4—4.

5—5 are flaps on opposite sides of the garment and secured thereto to the rear of the slits, in which the lacings 4—4 are provided.

6 is the abdominal pad proper, which may 40 be made of any suitable material, preferably elastic, this pad being connected at one edge by the lacing 7 to one of the flaps, while the lacing 8 may be detachably connected to studs or hooks 9, to connect and disconnect 45 the other edge of the body 6, from the other flap 5. The particular method of connecting the flaps 5—5 to the body 6 is, of course, immaterial, but it is preferably such that will enable the wearer to not only properly ad- 50 just the same to her particular figure, but

such as will also permit of a ready attachment and detachment.

When the abdominal support has been put in place and properly adjusted (say as shown in Fig. 1) the front portions 3—3 of the corset may be fastened together, whereupon by means of the lacings 4—4, the lower ends of the front portion may be properly adjusted and accommodated to the shape of the abdomen after the supporter member has been 60 adjusted. Thus, when once adjusted to any particular figure, the garment may be applied and removed without further re-adjustment.

It will be seen that the strain of the sup- 65 porter is taken directly from the hips and the rear, and all strain thereof is removed from the lacings 4—4. The flaps 5—5, as well as the supporter, extend below the edge of the front portion and that much of the garment 70 as extends over the hips. The back portion, therefore, extends well down on the figure so that no injurious strain is transmitted to the small of the back. The over-lying front pieces prevent the supporter from working 75 up, or from becoming wrinkled. They also serve to cover and protect the fastenings 7—8—9. By this particular arrangement, unsightly bulging of the outer garment is prevented.

80 In the particular form shown, the corset is of the "waist" type with extensions over the shoulder, but, of course, my invention is equally applicable whether the garment be of the plain corset type or of the waist type. 85

What I claim is—

1. In a corset, a body portion provided with adjustable extension means at the hips, and an abdominal pad secured to the inside of the body portion at the back and provided 90 with elastic extension means at one side of the center of the abdominal region for adjusting said extension, the front of the body portion of the corset being adapted to be fastened outside of and substantially covering the abdominal pad whereby the strain on the lower front portion of the corset is relieved. 95

2. In a corset, a body portion comprised of two halves adjustably connected together in back and provided with fastening means 100

in front, means for adjustably extending the lower edges of the two halves, an abdominal pad having its rear ends secured to the inside of the two rear halves of the body portion, 5 and means for adjustably extending said pad, the front of the body portion extending down over and substantially covering said

pad in the abdominal region whereby the strain on the lower front portion of the corset is relieved.

IDA M. BOND.
